UNITED STATES PATENT OFFICE.

THOMAS NATHAN RUSSELL, OF CHICAGO, ILLINOIS, ASSIGNOR TO CHICAGO-CLEVE-
LAND CAR ROOFING COMPANY, OF CHICAGO, ILLINOIS, A CORPORATION OF ILLI-
NOIS.

CAR-ROOF.

1,378,057.

Specification of Letters Patent. Patented May 17, 1921.

Application filed October 22, 1919. Serial No. 332,475.

To all whom it may concern:

Be it known that I, THOMAS NATHAN RUSSELL, a citizen of the United States, residing in Chicago, in the county of Cook and State 5 of Illinois, have invented a new and useful Improvement in Car-Roofs, of which the following is a specification.

The invention relates to car roofs in which 10 separate metal sheets rest, with some freedom for horizontal yielding or movement, on a top sheathing or suitable framework, and are joined together by upstanding seams formed by the upwardly bent side edges of the sheets loosely but securely interengaged 15 with seam caps to form water-tight seams, said seams extending from the ridge to the eaves of the roof.

It is an object of my invention to eliminate side fasciae so that the goods-containing 20 body of the car may be made as wide as possible and still go safely through tunnel clearings; a further object of the invention is to secure the eaves edges of the roof sheets on top of and entirely within the outer side 25 lines of the car and independent of the extreme side edges of the roof sheathing or frame; a further object is to permit, in such a narrowed construction as that above mentioned, of individual horizontal play of the 30 roof sheets, so as to prevent strains on the sheets and on their securing means.

With such objects in view, as well as other advantages which may be incident to the use of the improvements, the invention consists in the parts and combinations thereof hereinafter set forth and claimed, with the understanding that the several necessary elements constituting the same may be varied in proportions and arrangement without departing from the nature and scope of the invention.

In order to make the invention more clearly understood there are shown in the accompanying drawings means for carrying the same into practical effect, without limiting the improvements, in their useful applications, to the particular constructions which, for the purpose of explanation, have been made the subject of illustration.

50 In the said drawings:—

Figure 1 is a vertical cross-sectional view showing a portion of the roof and taken at the eaves of the car.

Fig. 2 is a perspective view of the eaves hook strip, partly broken away. 55

Fig. 3 is a perspective view of the eaves flashing, partly broken away.

Fig. 4 is a section on line IV—IV of Fig. 1.

Fig. 5 is a vertical section across the ridge 60 of the roof.

Fig. 6 is a section on line VI—VI of Fig. 1, looking toward the eaves, the top sheathing, the side plate and the side sheathing being omitted. 65

Referring to the drawings, 1 is a side plate of the roof frame, 2 the side sheathing, and 3 the top sheathing. The latter is formed at the eaves with a recess 4 for the reception of the means by which the eaves 70 ends of the roof sheets are confined and held from upward movement, with a capacity for some horizontal movement without imposing strains upon one another or upon their securing means. 75

5 is an eaves hook strip secured to the top sheathing and side plate in the recess 4 by nails 6 which are driven down through the top sheathing and into the side plate. With said hook strips are loosely engaged hooks 7 80 which consist of downwardly and inwardly turned portions of the ends of the roof sheets.

With this loose eaves seam is combined an eaves flashing and fascia element consisting of a vertical flange 8, which is secured to the side of the car by nails 9, and an inwardly and upwardly inclined flange 10 which enters the seam above the hook strip 5 and below the roof sheet hook 7, so as not 90 to interfere with the functions of said seam but so as to exclude any leakage from the joints where the metal parts come against the sheathings. The inner edge of the flashing is upturned as shown at 11 to insure the back flow of any water which may be dashed into the seam under the roof sheets. 95

The upstanding and uniting seam of the roof sheets 12 is shown at 13 and preferably 100 comprises an inverted U-shaped seam element 14 formed on the adjacent edges of the roof sheets, which elements engage over the upstanding flanges 15 of a tubular seam cap 16, so that the arched top of the cap 105 incloses all of said parts 14 and 15 (Fig.

4) and the roof sheets and cap can only be assembled and separated by endwise sliding in the direction of the length of the cap.

It will be seen that the structure of the 5 seam formed by said parts is such that there may be a yielding of the sheets or sliding of the two roof sheets relative to each other in directions transversely of the car, and also the sheets may yield slightly 10 toward and from each other without impairing the security of the seam.

The eaves end of the seam 13 is inclosed and somewhat loosely secured by a seam clip 18 having lateral flanges 19 and fingers 23 15 which engage above and confine the horizontal portions of the roof sheets at the sides of the seam. 24 is an inwardly extending flange of the clip 18 which, together with the fingers 23, partly encircle, 20 engage beneath and support the outer end of the seam cap so as to take the weight of the seam elements and prevent it from being imposed on the sliding joint formed by the flanges 5 and 7 of the hook strip and 25 roof sheet. The seam clip also comprises a vertical shank 20 which is secured to the roof frame by a bolt 21 passing through the side sheathing and side plate and by a nail 22 which maintains the proper vertical position of the seam clip.

My improvement effects a material saving in the elimination of the fascia, and any increase of cost due to greater width of the car body goes directly to increase in the 35 capacity of the car.

The eaves flashing is less liable to injury when it is applied directly on the car body instead of on a projecting part like a fascia, and the flashing takes the place of a fascia, 40 and is in effect a fascia element in confining the upper edge of the side sheathing.

By this construction replacement and repairs of the roof sheets and their connected parts are greatly facilitated, with saving of 45 time and labor.

What is claimed is—

1. In a car roof, the combination of a roof frame, a top sheathing carried thereby, roof sheets united in a loose seam which permits 50 individual movement of each sheet, the eaves ends of the roof sheets being formed with downwardly and inwardly bent hooked flanges, an eaves hook strip attached to the body of the car near the eaves and formed 55 with outwardly extending hooked flanges which are loosely engaged with those of the roof sheets, an eaves flashing having a vertical flange which is directly engaged with and confines the side sheathing of the car 60 and having a top flange which enters the eaves seam above a portion of the eaves hook strip and below the hooked flange of the roof sheets, and a seam clip attached directly to the side 65 sheathing and inclosing and supporting the outer end of the seam cap and loosely confining the eaves ends of the roof sheets.

2. In a car roof, the combination of a roof frame, a top sheathing carried thereby, roof sheets having upstanding downwardly hooked side flanges, a seam cap having inwardly turned and upwardly hooked side flanges which are engaged with the said flanges of a pair of adjacent roof sheets to form a loose seam, the eaves ends of the 70 roof sheets being formed with downwardly and inwardly bent hooked flanges, an eaves hook strip attached on the top of the top sheathing near the eaves and formed with outwardly extending hooked flanges which 75 are loosely engaged with those of the roof sheets, an eaves flashing having a vertical flange which is directly engaged with the side sheathing of the car and having a top flange which enters the eaves seam above 80 a portion of the eaves hook strip and below the hooked flange of the roof sheets, and a seam clip attached directly to the side 85 sheathing and inclosing and supporting the outer end of the seam cap and loosely confining the eaves ends of the roof sheets.

3. In a car roof, the combination of a roof frame, a top sheathing carried thereby, roof sheets having upstanding downwardly hooked side flanges, a seam cap having inwardly turned and upwardly hooked side flanges which are engaged with the said flanges of a pair of adjacent roof sheets to form a loose seam, the eaves ends of the 90 roof sheets being formed with downwardly and inwardly bent hooked flanges, an eaves hook strip having an outwardly extending flange attached on the top of the top sheathing near the eaves and formed with outwardly extending hooked flanges which are 95 loosely engaged with those of the roof sheets, an eaves flashing having a vertical flange which is directly engaged with the side sheathing of the car and confines the upper edge of said sheathing, and having a top 100 flange which enters the eaves seam above a portion of the eaves hook strip and below the hooked flange of the roof sheets, and a seam clip attached directly to the side 105 sheathing and inclosing and supporting the outer end of the seam cap and loosely confining the eaves ends of the roof sheets.

4. In a car roof, the combination of a roof frame, a top sheathing carried thereby, roof sheets united in a loose seam which permits 110 individual movement of each sheet, the eaves ends of the roof sheets being formed with downwardly and inwardly bent hooked flanges, an eaves hook strip secured to the top sheathing well within the eaves line of 115 the car and formed with outwardly extending hooked flanges which are loosely engaged with those of the roof sheets, and a structurally independent eaves flashing secured directly to the side sheathing of the 120 roof sheets.

car independently of the hook strip and having a vertical flange that depends from the eaves line and a top flange that enters the eaves seam above a portion of the eaves hook strip and below the hooked flange of the roof sheets, substantially as specified.

5. In a car roof, the combination of a roof frame, a top sheathing carried thereby, roof sheets united in a loose seam which permits individual movement of each sheet, the eaves ends of the roof sheets being formed with downwardly and inwardly bent hooked flanges, an eaves hook strip secured to the top sheathing well within the eaves line of the car and formed with outwardly extending hooked flanges which are loosely engaged with those of the roof sheets, a structurally-independent eaves flashing secured directly to the side sheathing of the car and having a vertical flange that depends from the eaves line and a top flange that enters the eaves seam above a portion of the eaves hook strip and below the hooked flange of the roof sheets, and a seam clip attached directly to the side sheathing and inclosing and supporting the outer end of the seam cap and loosely confining the eaves ends of the roof sheets, substantially as specified.
- 10 6. In a car roof having a roof frame, a top sheathing carried thereby, and roof sheets adapted to be united in a loose seam which permits individual movement of each

sheet, the eaves ends of the car sheets being formed with downwardly and inwardly bent hooked flanges: an eaves hook strip embodying a substantially flat member having a horizontal bottom flange which is secured on the top sheathing and terminating well within the eaves line of the car, said member having an outwardly extending hooked flange adapted to loosely engage the roof sheet eaves flanging and to accommodate a flashing strip interposed between said roof sheet flanging and the aforesaid substantially flat member of such hook strip; substantially as specified.

7. In a car roof, in combination, a metallic fascia element, side sheathing directly on which said fascia element is applied so as to confine the same, a roof frame to which the side sheathing is confined, roof sheets united in a loose seam allowing individual movement of the sheets relative to the eaves of the car, and a longitudinal eaves hook strip which confines the eaves edges of the roof sheets in a loose seam permitting them to have longitudinal and transverse movement, the upper part of said fascia element being inserted under the eaves ends of the roof sheets and into the hook of said eaves hook strip.

In testimony whereof I have hereunto set my hand.

THOMAS NATHAN RUSSELL.
